FEEDING MECHANISM FOR SEWING MACHINES

Nicholaus Knaus, Newark, N. J., assignor to The Singer Manufacturing Company, Elizabeth, N. J., a corporation of New Jersey

Application May 7, 1941, Serial No. 392,211

15 Claims. (Cl. 112—209)

This invention relates to feeding mechanisms for sewing machines and more particularly to that type of feeding mechanism known as a "differential feed" in which two work-feeding elements are adapted so to be actuated as to exert unequal feeding actions on the work, thereby to either "stretch" or "full" the work as required.

The invention has as a primary object to provide an improved differential feeding mechanism for sewing machines in which main and auxiliary feeding elements may be given the same work-feeding movement; in which a major adjustment is provided for simultaneously varying the amplitude of movement of both work-feeding elements; and in which an individual adjustment is provided for varying the amplitude of movement of each feeding element, whereby each feeding element may be given either a greater or a less work-advancing movement than the other.

A further object of the invention is to provide improved means, readily accessible to the hand of the operator, for varying the action of that one of the feeding elements which, in normal use, most frequently requires regulation.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is a vertical sectional view illustrating a portion of an overedge sewing machine embodying the present invention.

Fig. 2 is a perspective view of the improved feeding mechanism showing it operated from the main shaft of the sewing machine.

Fig. 3 is a horizontal sectional view taken substantially on the line 3—3 of Fig. 1.

Fig. 4 is a rear view, looking in the direction indicated by the arrow 4 in Fig. 1, of a portion of the sewing machine and the improved feeding mechanism.

Fig. 5 is a vertical sectional view taken substantially on the line 5—5 of Fig. 3.

Fig. 6 is detail view, partly in section, illustrating the means for adjusting the connection between one arm of a feed-rocker and the auxiliary feed-bar.

Fig. 7 is a detail sectional view through the feed-rocker showing the connection between one

of the feed-rocker arms and a link for actuating the auxiliary feed-bar.

Referring more specifically to the drawings, the invention is illustrated as embodied in an over-edge sewing machine similar to that disclosed in my United States Patent No. 2,238,796, Apr. 15, 1941, and comprising a main frame including a base 1 having upstanding portions 2 providing bearings in which is journaled a rotary main shaft 3 driven from any suitable source of power. The frame supports stitch-forming mechanism including a reciprocating curved eye-pointed needle 4 and looper mechanism (not shown), a work-trimming mechanism (not shown) and a frame-hood 5 which overlies and protects portions of the stitch-forming and work-trimming mechanisms.

The improved feeding mechanism also is supported by the machine frame and comprises a horizontally disposed main feed-bar 6 carrying, at its forward end, a main feed-dog 7 which is located and operates wholly rearwardly of the stitching point. A horizontally disposed auxiliary feed-bar 8 extends parallel with the main feed-bar and carries at its forward end an auxiliary feed-dog 9 which is located and operates mainly in front of the stitching point. The main and auxiliary feed-bars are formed with fork portions 6^a and 8^a, respectively, which embrace blocks 10 and 11 surrounding a feed-lift eccentric 12 secured upon the forward end of the main shaft 3. The rearward ends of the feed-bars 6 and 8 are formed as forks 6^b and 8^b which slidingly embrace blocks 13 and 14 journaled on a pin 15 mounted eccentrically in a supporting member 15^a secured to the machine frame.

Endwise reciprocatory motions are transmitted to the feed-bars 6 and 8, and the feed-dogs carried thereby, from an eccentric 16 (Fig. 2) secured upon the main shaft 3. These endwise motions are effected in timed relation with the up and down motions of the feed-bars under the influence of the eccentric 12 to give to the feed-dogs the conventional four-motioned feeding movements. The feed-drive eccentric 16 is surrounded by a strap 17 comprising one end of a pitman 18, the other end of which is connected to the free end of a rock-arm 19 secured upon a rock-shaft 20 journaled horizontally in the machine frame. Secured upon the shaft 20, adjacent the end thereof remote from the rock-arm 19, as by means of set screws 21, is a feed-rocker 22 having, at its opposite ends, upstanding arms 23 and 24 adapted to be connected to

actuate the main and auxiliary feed-bars 6 and 8, respectively. The feed-rocker 22 is provided, below the shaft 20, with a weighted portion W designed to counterbalance the weight of the arms 23 and 24. Slidingly mounted on the arm 23 is a U-shaped strap 25 to which is pivoted, by means of a stud 26, one end of a link 27 pivotally connected by a stud 28 to the main feed-bar 6. The strap 25 carries a clamp-shoe 29 engaging the rear edge of the arm 23 while the stud 26 carries a clamp-screw 30 adapted to engage the forward edge of the arm, thereby to draw the shoe into clamping contact with the arm to secure the strap in any adjusted position on the arm 23. The arm is of arcuate form, the axis of curvature being the center of the stud 28. From the foregoing it will be understood that the feed-rocker is oscillated about the axis of the shaft 20, and, through the arm 23, strap 25, stud 26 and link 27, transmits lengthwise movements to the main feed-bar 6. The amount of lengthwise movement transmitted to the feed-bar from any given degree of oscillation of the shaft 20, is dependent upon the setting of the strap 25 on the arm 23. This setting may be varied by loosening the clamp-screw 30 and manually shifting the strap on the arm 23 after which it is again clamped by tightening the screw 30.

The arm 24 is similar to the arm 23 and has slidingly mounted thereon a second U-shaped strap 31, provided with a stud 31^a which is connected by a link 32 with the auxiliary feed-bar 8. The link 32 is connected to the auxiliary feed-bar by a pivot 33 which is substantially in alignment with the stud 28. Thus it will be understood that the auxiliary feed-bar is given endwise movements by oscillation of the shaft 20, the amount of movement for any given degree of oscillation of the shaft depending upon the setting of the strap 31 on the arm 24. As shown most clearly in Fig. 7, the strap 31 carries a shoe 50 having a convex face 50^a which engages the concave edge of the arm 24, and a shoe 51 having a concave face 51^a which engages the convex edge of the arm. The shoe 51 also has on its outer face a concave surface 51^b adapted to receive the periphery of a washer 52 journaled eccentrically on a clamp-screw 53 connecting the free ends of the strap 31. The washer 52 is provided with a plurality of radially extending holes 54 adapted to receive the end of a pin, or other element, by means of which the eccentric washer may be rotated on the screw 53, thereby to shift the shoe 51 toward the arm 24 and compensate for wear in the parts.

The eccentric 16 which oscillates the shaft 20 is preferably of the adjustable type in which the eccentric is mounted on a plate 34 slidingly fitted in a collar 35 secured to the main-shaft. The plate 34 is adapted to be shifted lengthwise, to vary the eccentricity of the eccentric 16 relative to the axis of the shaft 3, and thereby vary the degree of oscillation of the shaft 20, by rotation of an adjusting screw 36 carried by the collar 35, as is well understood.

In operation, the auxiliary feed requires adjustment more frequently than does the main feed. Therefore, means is provided whereby the operator may readily effect the required adjustments of the auxiliary feed. This means comprises an adjustable three-armed lever L of which one arm 37 is journaled upon a shoulder screw 38 threaded into the machine frame as shown most clearly in Figs. 2 and 3. A second

5 arm 39 of the lever extends rearwardly and downwardly from the arm 37 and has secured to it at one side, by screws 40, a block 41 formed with an arcuate groove 42 which faces the arm 24 and receives a stud 43 carried by and projecting laterally from the strap 31. The third arm 44 of the lever L extends upwardly to a position immediately beneath the frame-hood 5 and has its upper end in vertical alignment with a slot 45 in said hood. Threaded into the upper end of the arm 44 is the shank of a clamp-screw 46 which extends through the slot 45 and has a shoulder 47 adapted to bear upon the frame-hood and a knurled portion 48 by which the screw may be turned to clamp the lever L in its various positions of adjustment. The screw 46 forms, in effect, a portion of the lever L and therefore may be considered to be a part thereof.

20 The center about which the arcuate groove 42, in the block 41, is formed is located materially below the axis of the pivot screw 38 for the lever L and in the uppermost position of the lever that center is adjacent the axis of the shaft 20. Therefore swinging of the lever L about its pivot will cause the walls of the groove 42 to exert a cam action on the stud 43 thus shifting the strap 31, and the attached end of the link 32, lengthwise of the arm 24 thereby varying the extent of endwise movement transmitted to the auxiliary feed-bar 8.

30 In any given setting of the adjustable eccentric 16 rotation of the main shaft 3 will cause the shaft 20, and the feed-rocker 22 attached thereto, to be given a definite number of degrees of oscillation. With the straps 25 and 31 adjusted to their uppermost positions on the arms 23 and 24 the feed-bars 6 and 8 will be given the maximum feed strokes available under that particular setting of the eccentric, which feed strokes will be equal, thereby giving to the main and auxiliary feed-dogs synchronous movements of equal amplitude. If either the strap 25 or the strap 31 is then adjusted downwardly on its supporting arm the specific feed-bar connected with that strap will be given a reduced movement. The lever L affords convenient means whereby the operator may vary the position of the strap 31, thereby to either increase or decrease the feeding stroke of the auxiliary feed-bar. Inasmuch as the strap 25, connected with the main feed-bar, requires only infrequent adjustment, the adjusting means therefor hereinbefore described will suffice. In practice, the strap 25 is usually secured to the arm 23 at an intermediate point thereon so that by manipulation of the lever L the auxiliary feed-dog may be given either a greater or less amount of movement than the main feed-dog.

40 In the sewing of certain materials, such for example as "rayon" it is desirable that the material be stretched during sewing. When sewing such materials the auxiliary feed-dog 9 is given a shorter feeding stroke than the main feed-dog 7. In sewing stretchy materials, such for example as knit goods, it is desirable that the material be "fullled" or crowded in ahead of the stitching point. This is effected by giving the auxiliary feed-dog a greater feeding movement than the main feed-dog.

50 From the foregoing it will be apparent that this invention has provided an improved feeding mechanism for sewing machines having a main adjustment for simultaneously regulating the action of both main and auxiliary feed-dogs and in which separate adjustments are provided for independently regulating the action of each feed-

dog. It will also be apparent that the invention has provided simplified means, readily accessible to the hand of the operator, for regulating the action of the auxiliary feed either while the machine is at rest or in operation.

Having thus set forth the nature of the invention, what I claim herein is:

1. In a sewing machine having main and auxiliary feeding mechanisms including main and auxiliary feed-dogs arranged in tandem with one of said feed-dogs located mainly in rear of the stitching point and the other feed-dog located mainly in advance thereof, the improvement which consists in the provision of a single means for varying the action of both feeding mechanisms, and individual means for selectively varying the action of each feeding mechanism.

2. In a sewing machine having a drive-shaft, a main feeding mechanism and an auxiliary feeding mechanism including main and auxiliary feed-dogs arranged in tandem with one of said feed-dogs located mainly in rear of the stitching point and the other feed-dog located mainly in advance thereof, the improvement which consists in the provision of an adjustable eccentric on said drive-shaft, means connecting said eccentric to actuate both of said feeding mechanisms, means for varying the eccentricity of said eccentric thereby to vary the action of both of said feeding mechanisms, and individual means for selectively varying the action of each of said feeding mechanisms.

3. A sewing machine having main and auxiliary feed-bars, a feed-dog connected to each of said feed-bars, a feed-rocker having two arms each connected to actuate one of said feed-bars, and means to vary the point of connection between each feed-bar and its connected arm thereby individually to vary the feeding stroke transmitted to each of said feed-bars by said feed-rocker.

4. A sewing machine comprising a rotary drive-shaft, a rock-shaft, means connecting said drive-shaft with said rock-shaft whereby oscillations are transmitted to the latter from the former, a two-armed feed-rocker secured to said rock-shaft, a main feed-bar connected with one of the arms of said feed-rocker, an auxiliary feed-bar connected with the other arm of said feed-rocker, and individual means for adjusting the connection between each of said rocker arms and its associated feed-bar thereby selectively to vary the extent of movement of each of said feed-bars under the influence of said feed-rocker.

5. A sewing machine comprising a rotary drive-shaft, a rock-shaft, means for oscillating said rock-shaft from said drive-shaft, a feed-rocker secured upon said rock-shaft and provided with two arcuate arms, a main feed-bar, an auxiliary feed-bar, a link pivotally connected to each of said feed-bars and adjustably connected with one of said arms, the center of curvature of each of said arms being located substantially at the point of connection between its associated link and the feed-bar actuated thereby, and means to vary the point of connection of each of said links with its associated rocker arm to vary the amount of endwise movement transmitted to the connected feed-bar.

6. A sewing machine comprising a rotary drive-shaft, an eccentric thereon, a rock-shaft, a rock-arm thereon, a pitman connecting said eccentric with said rock-arm thereby to effect oscillations of said rock-shaft from rotations of

said drive-shaft, means to vary the eccentricity of said eccentric to vary the degree of oscillation of said rock-shaft, a feed rocker secured upon said rock-shaft and provided with two arms, a main feed-bar, an auxiliary feed-bar, two links each having one end slidably connected with one of said arms and its other end pivotally connected to one of said feed-bars for transmitting endwise reciprocation to said feed-bars from the oscillatory motions of said feed-rocker, and individual means for adjusting the point of connection between each of said links and its associated rocker-arm thereby to vary the amount of endwise movement transmitted to the feed-bar connected therewith.

7. A feeding mechanism for sewing machines comprising a feed-rocker having two arms, a member slidably mounted on one of said arms, means for oscillating said feed-rocker, a main feed-bar adjustably connected with the other of said arms, an auxiliary feed-bar, a link pivotally connected at one end to said auxiliary feed-bar and at its other end to said member to transmit reciprocating motions to said auxiliary feed-bar from the oscillatory motions of said feed-rocker, and means including a manually adjustable lever operatively connected with said member for adjusting the position of said member on the first mentioned arm thereby to vary the movement transmitted to said auxiliary feed-bar by said feed-rocker.

8. In a sewing machine having a frame, a rock-shaft journaled in said frame and means to oscillate said rock-shaft; a feeding mechanism comprising a feed-rocker secured upon said rock-shaft and having a pair of spaced arms, a main feed-bar operatively connected with a first one of said arms, an auxiliary feed-bar, a link pivotally connected at one end to said auxiliary feed-bar and slidably connected at its other end with the second one of said arms, a feed-regulating lever pivotally mounted on said frame and operatively connected to shift the connection between said auxiliary feed-bar and said second arm thereby to vary the extent of movement transmitted to said auxiliary feed-bar by said feed-rocker.

9. In a sewing machine having a frame and a drive-shaft journaled therein; a differential feeding mechanism comprising a two-armed feed-rocker, means actuated by said drive-shaft for oscillating said feed-rocker, main and auxiliary feed-bars, a feed-dog carried by each feed-bar, means including a manually actuatable clamp for adjustably connecting said main feed-bar with one of the arms of said feed-rocker, means including a link pivotally connected at one end to said auxiliary feed-bar and having its other end slidably connected to the other arm of said feed-rocker for transmitting endwise reciprocations to said auxiliary feed-bar, and a lever pivotally mounted on said frame and operatively connected with said link and having a portion readily accessible to the operator for adjusting the point of connection of said link with said other rocker-arm thereby to vary the amplitude of motion transmitted to said auxiliary feed-bar by said feed-rocker.

10. A differential feeding mechanism for a sewing machine having a frame, comprising a rock-shaft journaled in said frame, means to oscillate said rock-shaft, a feed-rocker secured upon said rock-shaft and having a pair of arms, main and auxiliary feed-bars each operatively

connected with one of said arms, the connection between the auxiliary feed-bar and one of said arms including a member slidably mounted on the arm, and feed-regulating means including a three-armed lever having one arm pivotally connected to said frame, the second arm being operatively connected with the member slidably mounted on one arm of the feed-rocker and the third arm extending to a position where it is readily accessible to the operator for manual manipulation to vary the action of said auxiliary feed-bar.

11. A differential feeding mechanism for a sewing machine having a frame, comprising an oscillatory feed-rocker provided with a pair of arms, a main feed-bar adjustably connected to and actuated by one of said arms, a member mounted on and adjustable lengthwise of the other of said arms, an auxiliary feed-bar operatively connected with said member for actuation by said feed-rocker, means to shift said member on said arm thereby to vary the action of said auxiliary feed-bar, said means including a manually adjustable lever mounted on said frame and operatively connected with said member, and means to lock said lever in its various positions of adjustment.

12. A differential feeding mechanism for a sewing machine having a frame, comprising an oscillatory feed-rocker provided with a pair of arms, a main feed-bar actuated by one of said arms, a member mounted on and adjustable lengthwise of the other of said arms, an auxiliary feed-bar operatively connected with said member for actuation by said feed-rocker, means to shift said member on said arm thereby to vary the action of said auxiliary feed-bar, said means comprising a manually adjustable lever pivoted on said frame and having a portion readily accessible to the operator, a cam connection between said lever and said member whereby adjustment of said lever shifts said member and varies the action of said auxiliary feed-bar, and means to lock said lever in its adjusted positions.

13. A sewing machine comprising a frame, main and auxiliary feed-bars supported thereon, a feed-dog carried by each feed-bar, an oscillatory feed-rocker having a pair of arms each

operatively connected with one of said feed-bars for giving to said feed-bars endwise reciprocations, means for varying the connection between the auxiliary feed-bar and its associated rocker-arm thereby to vary the extent of reciprocation of said auxiliary feed-bar, said means comprising a member slidably mounted on said associated rocker-arm and connected with the auxiliary feed-bar, a stud projecting from said member, 5 a manually actuatable feed-regulating lever pivotally mounted on said frame, a cam carried by said lever and engaging said stud, means for turning said lever about its pivot to cause said cam to shift said stud and member on the associated rocker-arm, and means for locking said lever in its adjusted positions.

14. A sewing machine comprising a frame, main and auxiliary feed-bars supported thereon, a feed-dog carried by each feed-bar, a slotted frame-hood secured to said frame and overlying 20 said feed-bars, an oscillatory feed-rocker having a pair of arms each operatively connected with one of said feed-bars for giving to said feed-bars endwise reciprocations, an adjustable connection between one of said rocker-arms and the auxiliary feed-bar whereby the extent of movement transmitted to said auxiliary feed-bar by said feed-rocker may be varied, means including a plural-armed feed-adjusting lever pivotally mounted on said frame and having one portion 25 engaging the adjustable connection between the feed-rocker and the auxiliary feed-bar and another portion projecting through the slot in said frame-hood for easy engagement by the operator, and means to lock said lever in its adjusted positions.

15. In a sewing machine having main and auxiliary feed-dogs and means to impart the usual rising-and-falling movements thereto, the 30 improvement which consists in the provision of a feed-advance actuating element common to both feed-dogs with adjustable means to vary its amplitude of motion, and an individually adjustable branch connection from said actuating element to each of said feed-dogs, respectively, 35 to vary the amplitude of motion imparted thereto by said element.

NICHOLAUS KNAUS.
